FORCED FEED VAPORIZER

Original Filed July 10, 1925

INVENTOR
Charles A. Brewer,
BY
Alfred Glavin
ATTORNEY

UNITED STATES PATENT OFFICE

CHARLES A. BREWER, OF NOROTON HEIGHTS, CONNECTICUT

FORCED-FEED VAPORIZER

Substitute for application Serial No. 42,676, filed July 10, 1925. This application filed November 7, 1929.
Serial No. 405,528.

My invention relates to vaporizers, such as described in my original application, Serial No. 42,676, filed July 10, 1925, allowed May 3, 1926, forfeited Dec. 3, 1926, renewed March 10, 1927, re-allowed February 18, 1929, and again forfeited. This is a substitute for my former application filed July 10, 1925, Serial No. 42,676.

My invention relates, generally, to an improved construction of vaporizer; and, the invention has for its principal object to provide a novel construction of force feed vaporizer suitable for general use in vaporizing liquids of all kinds, and forcibly discharging or delivering the same to the place of use.

With the objects of the invention in view, the same consists, primarily, in the novel vaporizer apparatus hereinafter set forth; and, the invention consists, furthermore, in the novel arrangements and combinations of the various devices and parts, as well as in the details of the construction of the same, as more fully described in the following specification, and set forth in the claims appended thereto.

The invention is shown by way of illustration in the accompanying drawings, in which:—

Fig. 1 is a vertical longitudinal section of the novel vaporizer apparatus, made according to and embodying the principles of this invention; Fig. 2 is a transverse vertical section, taken on line 2—2 in Fig. 1; and Fig. 3 is another detail transverse vertical section, taken on line 3—3 in said Fig. 1, drawn to a larger scale.

Similar characters of reference are employed in all the views, to indicate corresponding parts.

The novel vaporizer device comprises a casing 5 which may be formed by a suitable casting, and which is shaped to provide an interior intake chamber 6. Leading into the lower end of said intake chamber 6 is an air-intake passage 7, which is preferably provided, at its outer end, with a butter-fly or throttle valve 8. The inner end of said air-intake passage 7 is upturned to extend vertically upward into said intake chamber 6, and is preferably internally shaped at its dis-

charge end so as to provide a restricted or Venturi tube portion 9. Also connected with said casing 5, in alignment with the upturned discharge end of said air-intake passage 7 below the same is a liquid intake chamber 10. Extending upwardly from said liquid intake chamber 10 into said upturned discharge end of said air-intake passage 7 is a liquid discharge nozzle 11, the upper discharge extremity of which is located within said restricted or Venturi tube portion 9 of said air-intake passage. The reference character 12 (Fig. 3) indicates any known form of float chamber device, adapted to control the delivery of the desired liquid from a suitable source of supply to said nozzle 11; a suitable delivery conduit or pipe 13 connecting said float chamber device with said liquid intake chamber 10. If desired, a suitable filter screen device 14 may be arranged within said liquid intake chamber 10, intermediate the delivery conduit or pipe 13 and the liquid discharge nozzle 11. It will be understood that any desired construction and arrangement of means for delivering a liquid through the delivery conduit or pipe 13 to said liquid intake chamber 10 to supply the discharge nozzle 11 may be employed, and I do not, therefore, limit myself to the use of the float chamber device 12, which is merely illustrative of one form of liquid delivery supply and control.

The casing 5 is closed on its forward side by a cover-plate 15, having a centrally disposed outwardly projecting neck 16 providing a discharge passage 17. Said neck 16 is externally threaded so that a casing 18 may be coupled therewith. Said casing 18 constitutes a vaporizing chamber 19, with which said discharge passage 17 communicates. Said casing 18 is so shaped or formed as to provide, in connection with its inner or rearward face, an annular space adapted to form a heating chamber 20, which may be closed by the opposed face of the cover-plate 15, a suitable gasket 21 being provided to form a tight joint. A suitable heating medium serves in connection with said heating chamber 20, for example an electrical heating element 22 mounted therein, which is adapted to generate heat to be transferred through the 100

walls of said casing 18 to said vaporizing chamber 19. The lower end of said vaporizing chamber 19 is preferably provided with a depending hollow extension 23 constituting a trap 24 to receive condensation or unvaporized accumulation of the liquid under treatment. Casing 18 is closed at its outer side by a suitable cover-plate 25, which is provided with a centrally disposed forwardly projecting internally threaded neck 26, into which may be threaded a discharge pipe or conduit 27 for conveying the generated vapor to the place of use or consumption.

Mounted within said intake chamber 6, for rotation therein in a transverse vertical plane, is a combined blower and nebulizer 28, the same being located intermediate the air-intake passage 7 and the discharge passage 17, so that it exerts a suction effect relative to the former and a propulsion effect relative to the latter.

Mounted within the vaporizing chamber 19, for rotation therein in a transverse vertical plane, is a rotary plate 29, the same being located intermediate the passage 17 and the vapor discharge conduit 27.

Said blower and nebulizer 28 and said rotary plate 29 may be driven in any manner and from any source of power found desirable. To such end, a shaft or spindle 30 is provided, upon which the said devices are fixed, said shaft or spindle 30 being driven by suitable power transmission means.

When the vaporizer apparatus is put in operation, it functions as follows:

The combined blower and nebulizer 28 is rapidly rotated within the intake chamber 6, with the result that a stream of air is sucked through the air-intake passage 7. The entering air stream is accelerated in movement as it passes through the restriction or Venturi tube portion 9, so that the liquid which is supplied to the discharge nozzle 11 is drawn or sprayed into the air stream, and roughly mixed therewith as it enters said intake chamber 6. The mixture of air and liquid thus drawn into the intake chamber 6 is thoroughly agitated by the rotating blower and nebulizer 28, so that the liquid is mechanically broken up into exceedingly minute particles, which are intimately mixed with and suspended in the air, forming a fine mist; in other words, the initially entering mixture of air and liquid is nebulized, i. e., turned into a mist or fog. Any heavy particles of liquid, not sufficiently broken up or nebulized by the agitating action of the blower and nebulizer 28, are thrown by centrifugal force to the outer circumferential walls of the intake chamber 6, down which they descend by gravity into a depending well or trap 31 at the lower portion of the casing 5. This well or trap is more or less heated by the heat conducted and transferred through its walls from the heating medium in the heating chamber 20, so

that the liquid collecting therein during operation of the apparatus is vaporized by the heat and returned into the mist discharged from the intake chamber 6 into the vaporizing chamber 19.

The mist or nebulized mixture of air and liquid formed in the intake chamber 6 as above described, is propelled from the outer side or face of the blower and nebulizer 28 so as to be forced outwardly from said intake chamber 6, through the passage 17 into the vaporizing chamber 19. As the mist-like mixture of air and liquid enters the heated vaporizing chamber 19 it impinges against the surface of the rotating plate 29, which is kept hot by the heat radiated into the vaporizing chamber from the heating chamber 20. The minutely divided particles of liquid upon striking the plate 29 are vaporized (or gassified, as the case may be) and the resultant vapor is forced onward, by the propulsion effects of the blower 28 to pass around the periphery of said plate 29 and thence outward through the discharge pipe or conduit 27 to the point of consumption or use. Any condensation accumulating in the vaporizing chamber 19 when the apparatus is idle, or under any other circumstances, will descend into the trap or well 24 and will be retained therein subject to the action of the heat within the vaporizing chamber, and conducted through the walls thereof, whereby the condensate will be eventually vaporized and discharged.

From the above description it will be quite apparent, that my novel vaporizing apparatus is capable of service in several fields. For example, it may be employed as a steam generator, in which case the liquid delivered to the apparatus would be water, which when mixed with air and nebulized, and thereupon subjected to heat in the vaporizing chamber, would be turned into steam which would be forcibly delivered through the discharge conduit or pipe 27 to the desired place of use. The apparatus in such case would serve as a continuously operating steam generator of the flash type. The above described use of my novel apparatus is well illustrated in my United States Letters Patent, No. 1,649,337, dated November 15, 1927.

Another field of service to which my above described vaporizing apparatus is applicable is that of carburetion of combustible liquid fuels, such as hydrocarbons.

I am aware that various changes may be made in the general arrangements and combinations of the parts of my novel vaporizer apparatus, as well as in the details of construction of the same, without a departure from the scope of this invention as above described and as defined in the appended claims, and therefore, I do not limit this invention to the exact arrangements and combinations

and the construction of the devices and parts as shown and described.

I claim:

1. A vaporizer apparatus, comprising a casing subdivided to provide an intake chamber and a vaporizing chamber with means of communication leading from the former to the latter, an air-intake means leading to said intake chamber, a liquid delivery nozzle provided in said air-intake means, means for supplying liquid to said nozzle, a rotatable blower and nebulizer in said intake chamber, a rotatable plate in said vaporizing chamber, means for heating the interior of said vaporizing chamber and said plate disposed therein, and a discharge conduit leading from said vaporizing chamber.

2. A vaporizer apparatus, comprising a chambered casing, means for admitting a mixture of air and liquid to said casing, a discharge conduit leading out of said casing, a plate within said casing forward of said discharge conduit, means for supplying heat to said plate, and a rotary blower and nebulizer in said casing intermediate said air and liquid admission means and said plate, said blower and nebulizer being adapted to exert a suction effect on said air and liquid admission means to draw a mixture of air and liquid into said casing and being further adapted to both nebulize said mixture and propel the same into impingement upon and around said plate and thence outwardly through said discharge conduit.

3. A vaporizer apparatus, comprising a casing subdivided to provide an intercommunicating intake chamber and vaporizing chamber, an air intake means leading into the rearward end of said intake chamber, a discharge conduit leading out of said vaporizing chamber, said air intake means having a Venturi tube portion, a liquid delivery nozzle disposed in said air intake means so as to terminate within said Venturi tube portion, means for supplying liquid to said nozzle, a rotary plate within said vaporizing chamber, means to supply heat to said vaporizing chamber and said plate, and a rotary blower and nebulizer in said casing intermediate said air and liquid intake means and said vaporizing chamber, said blower and nebulizer being adapted to exert a suction effect on said air and liquid intake means and to nebulize the mixture of air and liquid and propel the same into impingement upon and around said plate and thence outwardly through said discharge conduit.

4. A vaporizer apparatus, comprising a casing subdivided to provide an intake chamber and a vaporizing chamber with means of communication leading from the former to the latter, a heating means, a housing for said heating means intermediate said intake chamber and said vaporizing chamber, means for admitting a mixture of air and liquid

into said intake chamber, a rotary blower and nebulizer operative in said intake chamber to suck into the same the mixture of air and liquid and agitate the same and thereupon propel the same through said vaporizing chamber and its discharge conduit, and a rotary plate within said vaporizing chamber against which the mixture of air and liquid impinges when propelled through said vaporizing chamber.

5. A vaporizer apparatus, comprising a chambered casing to provide an intercommunicating intake chamber and vaporizing chamber, a heating means, a housing for said heating means intermediate said intake chamber and vaporizing chamber, a power driven shaft extending through said intake chamber into said vaporizing chamber, a plate fixed on said shaft for rotation therewith, in said vaporizing chamber, a blower fixed on said shaft for rotation therewith in said intake chamber, an air and liquid atomizing means entering said intake chamber on the suction side of said blower, means for supplying a liquid to said air and liquid atomizing means, a discharge conduit connected to said vaporizing chamber, said blower being adapted to propel in atomized mixture of air and liquid through said vaporizing chamber and in contact with said plate therein.

6. In a vaporizing device, an intake chamber, a means for supplying fluid to be vaporized to said chamber, a vaporizing chamber in open communication with said intake chamber, a heat-transmitting means interposed between said two chambers, a movable member in said intake chamber adapted to draw into said intake chamber the fluid supplied by said fluid supplying means and to convert said fluid into a mist, at the same time propelling said nebulized fluid into said vaporizing chamber, a movable member in said vaporizing chamber being in heat-transmitting relation to said heat-transmitting means and forming an impinging surface for the nebulized fluid, and a discharge conduit connected to said vaporizing chamber.

In testimony whereof I affix my signature.

CHARLES A. BREWER.
